DECK

Ernest M. Wichert, Wilkinsburg, Pa.

Application September 21, 1943, Serial No. 503,219

2 Claims.

(Cl. 94—13)

This invention relates to decks, and especially portable decks suitable for use as airplane runways, for vehicular traffic, for the storage and handling of materials, etc. This invention has to do with decks of the general type disclosed in my copending applications, Serial Nos. 473,586 and 503,218, but relates to a simplified construction in which no means separate from the deck panels is required to connect the panels together.

In decks of the type having panels hooked together by hooks integral with the panels as heretofore proposed the connections between panels have not been such as to enable the transmission of flexural stress. In other words, in decks of the type mentioned as heretofore proposed, although the panels have been fastened together so that they remain in assembly, the connections have not been such as to impart to the deck as a whole continuous or even semi-continuous characteristics but each panel has acted more or less independently so far as transmission of flexural stress is concerned.

I provide a portable deck which while it does not have the completely continuous characteristics of the decks of my said copending applications has characteristics approaching continuous characteristics and which are much more nearly continuous than the characteristics of decks having panels hooked together by hooks integral with the panels as heretofore proposed. I provide means for fastening adjacent panels together and also cooperating bearing means coacting with the fastening means to form a joint between the panels capable of transmitting flexural stress. The joint between adjacent panels does not have the completely continuous characteristics of the joints of my said copending applications because since the panels are fastened together by means forming parts of the panels themselves there must be sufficient looseness at the joint to enable the panels to be initially moved into and out of assembled position. However, after the relatively slight lost motion is taken up the joint between opposed connected panels has substantially continuous characteristics within the strength of the material employed.

I preferably provide cooperating hooks and portions with which the hooks engage to hold the panels together. Preferably the hooks face generally along the edge of the panel on which they are formed so that such panel is assembled with the opposed panel by positioning the hooks in proper relationship with the cooperating portions of the opposed panel and then relatively moving the panels generally parallel to the joint to engage

the hooks with the cooperating portions. I find it desirable to provide hooks on each of a pair of opposed panels, the hooks on the respective panels facing in opposite directions, so that when the panels are assembled each one hooks into the other. Cooperating with the hooks I provide bearing means to insure maintenance of the panels in proper relative position. As mentioned above, the hooks and the portions receiving them and the cooperating bearing means impart to the deck substantially continuous characteristics after the initial lost motion due to the looseness necessary to enable assembly of the panels is taken up.

Other details, objects and advantages of the invention will become apparent as the following description of a present preferred embodiment thereof proceeds.

In the accompanying drawings I have shown a present preferred embodiment of the invention, in which

Figure 1 is a fragmentary plan view of a deck made up of panels fastened together;

Figure 2 is an enlarged fragmentary plan view of one of the panels;

Figure 3 is a further enlarged fragmentary detail plan view showing opposed portions of two panels and how they are connected together;

Figure 4 is a cross-sectional view taken on the line IV—IV of Figure 3; and

Figures 5 and 6 are perspective views of cooperating portions of adjacent panels disassembled.

Referring now more particularly to the drawings, there is shown in Figure 1 a portable deck made up of sections or panels each designated by reference numeral 2. The panels are connected together by means forming parts of the panels themselves. Each panel consists of a body portion 3 and a peripheral flange 4. The body portion 3 is provided with elongated openings 5 formed, as described in my said copending application Serial No. 473,586, by slitting and then deforming the metal of the panel, flanges 6 surrounding the elongated openings adding strength to the structure. The elongated openings are arranged in rows and columns with adjacent openings in each row and column oriented at right angles to one another. With the arrangement disclosed the moment of inertia of each panel at all sections perpendicular to the plane of the panel and of a length in the plane of the panel equal to the smallest dimension of the panel in its plane is substantially the same so that the structure is exceptionally strong and rigid for the weight of material employed.

In the form of structure shown in the drawings

of the present application the panels are connected together at their longitudinal edges only and not at their ends. As shown in Figure 1, the ends of adjacent panels are slightly spaced apart to enable any panel to be moved lengthwise the distance necessary to disengage it from the panels with which it is connected at each side, as will presently be described.

Each panel has along one longitudinal edge a flange 7 which constitutes part of the continuous peripheral flange 4. The flange 7 consists of a downwardly and outwardly inclined portion 8 and an upwardly and outwardly inclined portion 9 joined to the portion 8 at its outer edge. The portions 8 and 9 form between them a trough or channel 10. Hooks 11 are formed integrally with the flange portion 9 and are arranged at intervals along the edge of the panel as shown. The hooks 11 are arranged in pairs, the pairs being spaced apart by a distance equal to the distance on centers between the elongated openings 5 at the edges of the panel and the hooks of each pair being spaced apart by a distance equal to the distance between the slots formed in the flanges 6 of such openings for receiving the hooks as will presently be described. The hooks face longitudinally of the panel, i. e., along the edge of the panel or along the joint between adjacent or opposed panels.

The opposite longitudinal edge of each panel has a flange 12 forming, like the flange 7, a portion of the continuous peripheral flange 4. The flange 12 is inclined downwardly and has formed integrally therewith hooks 13. The hooks 13 are likewise arranged in pairs, the pairs being spaced apart by a distance equal to the distance between the pairs of hooks 11 and the hooks of each pair being spaced apart by a distance equal to the distance between the pockets for receiving the hooks as will presently be described. The hooks 13 of one panel face longitudinally thereof in the direction opposite the direction in which the opposed hooks 11 of the adjacent panel face. The hooks 11 and 13 at opposite edges of any given panel all face in the same direction.

Formed partly in the body portion 3 of the panel and partly in the flange portion 8 are depressed straps 14. The material of the straps 14 is severed from the adjacent material along the side edges of the straps but not at the ends thereof. Hence a recess or pocket 15 is formed adjacent each strap 14 as clearly shown in Figures 4 and 5. These pockets 15 are to receive the hooks 13 when opposed panels are assembled.

Slots 16 are formed in the flanges 6 surrounding the elongated openings 5 at the edges of the panel as shown in Figures 3, 4 and 6. These slots 16 are to receive the hooks 11 when the panels are assembled. Bearing portions 17 are also formed on the same flanges 6 as clearly shown in Figures 3 and 4, these bearing portions being adapted to lie in the channel 10 when the panels are assembled as shown in Figure 4.

When it is desired to assemble two panels one of them is laid with the flange 7 extending generally downwardly as indicated in Figure 5 and an adjacent or opposed panel is brought alongside the first mentioned panel with the flange 12 generally parallel to the flange 7 as indicated by the relationship of Figures 5 and 6 of the drawings. The second panel is moved into engagement with the first panel so that the hooks 13 lie upon the straps 14 pointing toward the pockets 15 and the hooks 11 lie adjacent the slots 16 pointing toward them. At the same

time the bearing portions 17 lie in the channel 10 forming keys. There must be sufficient looseness to enable the adjacent panels to be assembled as just described and then to be moved relatively to each other to engage the hooks 13 in the pockets 15 and the hooks 11 in the slots 16. This, of course, is done by moving the panels in the directions in which the hooks face. After such movement has been completed and the hooks 13 have been engaged in the pockets 15 and the hooks 11 have been engaged in the slots 16 the panels will be interconnected so as to form what I term a semi-continuous structure as referred to above. The panels will move relatively to one another under stress to an extent sufficient to take up the lost motion necessarily provided for their assembly and disassembly, but after that lost motion is taken up the deck comprising the assembled panels assumes substantially continuous characteristics.

The assembled panels are suitably held in assembled relationship. This may be easily accomplished by bending over one or more of the hooks after the panels have been interengaged so as to prevent those hooks which are bent from sliding back out of the slots or pockets with which they cooperate. Preferably two hooks are thus bent at each joint, one at each end of the joint. Alternatively, if desired, a wedge or filler block may be inserted after assembly of the panels so as to lie between the shoulder 18 (Figure 3) at the rear of one of the hooks 11 and a portion of the flange 6 therebehind. Such wedge or filler block prevents relative movement of the panels 30 to disengage the hooks from the respective pockets and slots and thus insures maintenance of assembly of the panels. When it is desired to disassemble the panels the bent hooks are straightened out into their original positions or 40 if a wedge or filter block has been used it is removed. Then the panels are disassembled by relatively moving them in the direction opposite the direction in which the hooks point until the hooks are disengaged from the pockets and slots, 45 whereafter the panels may be lifted apart.

The panels are made in right-hand and left-hand sections or designs. Each longitudinal row of panels is of the same hand and alternate rows are of opposite hand. For example, the top panel 50 in Figure 1 is a left-hand panel, the two middle panels are right-hand panels and the bottom panel is a left-hand panel. The hand of a panel is determined by the direction in which its hooks face or point. With the construction disclosed 55 it is necessary for the hooks of adjacent panels to point in opposite directions in order that any panel or any number of panels may at will be removed from the deck.

While I have shown and described a present 60 preferred embodiment of the invention it is to be distinctly understood that the invention is not limited thereto but may be otherwise variously embodied within the scope of the following claims.

65 I claim:

1. A deck comprising a panel having a channel extending along its edge and an opposed panel having bearing means adapted to be positioned in said channel, each of the panels having hooks 70 and each of the panels also having portions with which the hooks of the other panel cooperate to maintain the panels in assembly, the hooks and cooperating portions coacting with the channel and bearing means to form a joint between the 75 panels capable of transmitting flexural stress.

2. A deck comprising a panel having channel means at an edge thereof and an opposed panel having bearing means adapted to be positioned in said channel means, each of the panels having hooks facing generally along the joint between the panels, the hooks of the respective panels facing in opposite directions, and each of the panels also having portions with which the hooks

of the other panel cooperate to maintain the panels in assembly, the panels being assembled by relative movement thereof in the direction in which the hooks face, the hooks and cooperating portions coacting with the channel and bearing means to form a joint between the panels capable of transmitting flexural stress.

ERNEST M. WICHERT.

CERTIFICATE OF CORRECTION.

Patent No. 2,376,989.

May 29, 1945.

ERNEST M. WICHERT.

It is hereby certified that error appears in the printed specification of the above numbered patent requiring correction as follows: Page 2, second column, line 40, for "filter" read --filler--; and that the said Letters Patent should be read with this correction, therein that the same may conform to the record of the case in the Patent Office.

Signed and sealed this 18th day of September, A. D. 1945.
